O. H. HANSEN.
METHOD OF TREATING CANNED FOODS.
APPLICATION FILED NOV. 9, 1918.

1,391,953.

Patented Sept. 27, 1921.

UNITED STATES PATENT OFFICE.

OSWALD H. HANSEN, OF PORT WASHINGTON, WISCONSIN, ASSIGNOR OF ONE-HALF
TO THE WISCONSIN CHAIR COMPANY, OF PORT WASHINGTON, WISCONSIN.

METHOD OF TREATING CANNED FOODS.

1,391,953.

Specification of Letters Patent. Patented Sept. 27, 1921.

Application filed November 9, 1918. Serial No. 261,791.

To all whom it may concern:

Be it known that OSWALD H. HANSEN, a citizen of the United States, residing at Port Washington, in the county of Ozaukee and State of Wisconsin, has invented a certain new and useful Method of Treating Canned Foods, of which the following is a specification.

This invention relates in general to an improved method of treating packed fluent substances, and relates specifically to an improved method of cooking, sterilizing, cooling or otherwise treating fluent foods packed in containers such as metal, glass or other receptacles.

An object of the invention is to provide a simple and efficient method of treating packed fluent substances.

It is common practice in the canning industry, to treat fluent foods by first cooking or sterilizing the same by the application of steam or other heating agency, and by subsequently cooling the substance. The material is ordinarily thus treated after it has been packed in air-tight containers such as cylindrical metal cans, which cans are only partially filled with the substance. The prior art abounds in devices for carrying on these treating operations. In all of the devices of the prior art which have attained any degree of commercial success, the successive cans are rotated about their longitudinal central axes while horizontally disposed, and are simultaneously urged along either an annular, a helical, a spiral or a rectilineal path during the treating operation. It has been found that during rotation of the cans about their horizontal axes and regardless of the direction of transportation through the treating chamber, a zone of quiescence is formed adjacent the center of the mass of substance packed in each container, thereby preventing uniform treatment of the material.

The present invention contemplates elimination of this defect in the prior methods of and apparatus for treating such substances. The prior defective treatment is remedied with the present invention by agitating the fluent contents of each can during its treatment, in order to produce uniform treatment of all portions of the mass. This improved result is accomplished by rotating the cans about axes which are inclined relatively to the horizontal, such rotation being

effected simultaneously with the transportation of the cans through the treating zone. The method of and apparatus for accomplishing the desired agitation, as well as other novel features and advantages, will be apparent from the following description.

The term "food" as employed herein is intended to include any substance containing food value of any kind. The term "fluent" includes any material capable of flowing, whether it be a liquid, a mixture of liquid and granular material, or finely divided granular material alone. It is moreover not desired to limit the scope of the invention by specifically describing it as applied to or associating the same with the industry of packing vegetables in metal containers, as the principles and features of the invention are capable of more general application.

A clear conception of the various steps of the process and of several embodiments of apparatus for exploiting the same, may be had by referring to the drawing accompanying and forming a part of this specification in which like reference characters designate the same or similar parts in the various views.

Figure 1 is a fragmentary part sectional side elevation of a cooking or sterilizing device for treating substances packed in cylindrical receptacles.

Fig. 2 is a part sectional end view of the cooking or sterilizing apparatus, looking toward the receptacle admission end, the section being taken along the line II-II of Fig. 1 looking in the direction of the arrow.

Fig. 3 is a fragmentary part sectional end view of the cooking or sterilizing apparatus, looking toward the receptacle discharging end, the section being taken along the line III-III of Fig. 1 looking in the direction of the arrow.

Fig. 4 is a fragmentary sectional side view of another form of cooking or sterilizing device for treating substances packed in cylindrical receptacles.

Fig. 5 is a central vertical section through a cylindrical can having its axis horizontally disposed, showing one position of the mass of substance when the can is being treated in a device of ordinary construction.

Fig. 6 is a central vertical section through a cylindrical can having its axis inclined relatively to the horizontal, showing one po-

sition of the mass of substance when the can is being treated in a device of improved construction.

The cooking or sterilizing device illustrated in Figs. 1, 2 and 3, comprises in general a main housing or casing 1 forming a chamber provided with the usual instrumentalities for heating the interior thereof, a helical can guide 7 stationarily supported within the casing 1, and a main can revolving reel or rotor consisting of a main shaft 2 and an angular series of parallel angle bars 6 associated with said shaft and centrally rotatably supported within the helical guide 7 and the casing 1. The casing 1 may be of any suitable form or structure and is provided with can inlet and discharge chutes 10, 21 respectively, located adjacent the opposite casing ends. The guide 7 comprises a helical T-bar stationarily supported with the helix axis inclined relatively to a horizontal plane by means of end spiders and longitudinal retaining plates 8. The proper inclination of the helical guide 7 is produced by means of an end support 9 which may be made of a vertical height necessary to produce the desired degree of inclination of the helix axis. The can revolving rotor is rotatably supported in end supports or bearings 3 formed in the guide spiders, and has its angle bars 6 drivingly connected to the shaft 2 by means of rotary end spiders 4. The bars 6 are held in proper spaced relation relatively to each other, by means of the end spiders 4 and intermediate supporting rings 5. The outwardly projecting flanges of the angle bars 6 form flights adapted to coact with the cylindrical side walls of the cans 16 in order to roll the cans along the cross member of the helical T-bar guide 7, while the inwardly extending flange of the T-bar is adapted to coact with plane can ends in order to confine the cans to a helical path of travel.

The cans 16 are fed into the casing 1 and in proximity to the revolving main rotor and helical guide 7, by means of the can inlet chute 10. The revolving main rotor is rotated by means of power applied to the pulley 12 associated with one end of a drive shaft 13, to the other end of which is connected a worm 14 which meshes with a worm wheel 15 secured to an end of the main shaft 2. The worm gearing is inclosed in a suitable housing for protection, see Fig. 2. The cans 16 are delivered from the casing 1 and into the discharge chute 21, by means of a discharge rotor 11 comprising a counter shaft 19, a rotor element 28 secured to the shaft 19, and a series of spaced parallel angle bars 18 secured to the element 28. The shaft 19 is rotatably supported in suitable bearings in the casing 1, with its axis parallel to the axis of the shaft 2, and is drivingly connected to the shaft 2 by means of spur

gears 22, 23. The can discharge rotor 11 is housed in a stationary casing 17 and is adapted to urge the cans 16 along a delivery guide 20 connecting the delivery end of the helical guide 7 with the delivery chute 21, 70 see Fig. 3.

The cooking or sterilizing device illustrated in Fig. 4, comprises in general a main housing or casing such as shown in Fig. 1, a helical-spiral can guide 7 stationarily supported within the casing, and a can revolving reel or rotor consisting of a main shaft 2 and an annular series of angle bars 6 associated with the shaft and rotatably supported within the guide 7. The guide 7 of this embodiment comprises a helical-spiral T-bar stationarily supported with its axis horizontally disposed, by means of end spiders and longitudinal retaining plates 8. The can revolving rotor is rotatably supported in end bearings with its axis horizontally disposed. The angle bars 6 are held in proper spaced relation relatively to each other and in proximity to the guide 7, by means of end spiders and intermediate supporting rings 5. 90 The bars 6 of this embodiment are not parallel but are inclined relatively to the axis of the main shaft 2. The outwardly projecting flanges of the angle bars 6 form flights adapted to coact with the cylindrical side walls of the cans 16 in order to roll the cans along the cross member of the helical-spiral T-bar guide 7, while the inwardly extending flange of the T-bar is adapted to coact with the plane can ends in order to 100 confine the cans to a helical path of travel.

During the normal operation of the device as a cooking apparatus, the chamber provided by the casing 1, is heated by means of steam, hot water or other heating agency. 105 The main can revolving rotor and the discharge rotor 11 are simultaneously rotated in the directions indicated by the arrows in Figs. 2 and 3, by means of power applied at the pulley 12. The successive cans 16 are 110 fed to the revolving rotor and into the gaps between successive bars 6, by means of the inlet chute 10. The outwardly projecting flanges of the bars 6 coact with the cylindrical side walls of the successive cans 16 rolling these cans about their own axes which are inclined relatively to a horizontal plane, and simultaneously revolving the rotating cans 16 about the axis of the shaft 2. The rotating revolving cans 16 are urged forwardly through the heating chamber by means of the helical guide 7, and are eventually successively delivered from the apparatus by means of the discharge rotor 11 which removes the treated cans 16 from the 120 periphery of the can revolving rotor and delivers them to the discharge chute 21.

The manner in which the mass of substance or material in each can 16 is moderately but thoroughly agitated and brought 130

into contact with the outer wall of the receptacle in order to produce efficient heat transfer, may be best perceived by referring to Figs. 5 and 6.

5 In the case of Fig. 5, the cylindrical can 16 has its longitudinal axis 27 horizontally disposed. The upper space 25 which is not filled by material 26, extends along the entire length of the can 16 and has a uniform segment-shape transverse cross section. As the can 16 of Fig. 5 is rotated relatively slowly about the horizontal axis 27, a practically cylindrical zone or core of quiescent material, is formed adjacent the axis 27, the position of this core relatively to the remainder of the mass remaining substantially fixed, thus avoiding effective heating or cooling as the case may be, of the material constituting this core, due to the surrounding layer of moving material which serves as an insulating jacket. This figure illustrates the position of the cans 16 and the results attained with the cooking, sterilizing or cooling devices of the prior art.

25 In the case of Fig. 6, the cylindrical can 16 has its longitudinal axis 27 inclined or transversely disposed relatively to the horizontal. In this case the space 25 is confined to the upper corner of the interior of the can 16 only, and has a transverse cross section of varying area. When a can 16 thus disposed, is rotated relatively slowly about its inclined axis 27, no definite core or zone of quiescence will form in the center of the mass of material, but instead, the mass will be moderately agitated and thoroughly mixed to bring all portions thereof in proximity to the can wall. In this manner uniform treatment of all portions of the mass is assured, thereby increasing to a maximum the capacity of the apparatus and effecting most efficient treatment.

In either of the cases illustrated, the receptacle or can 16 must not be rotated about its own axis 27 at a speed which will overcome the effects of gravity, and which will result in the production of a central core or air chamber. While centrifugal force is instrumental in producing both the undesirable result of the prior art and the desirable result of the present invention, the latter result is primarily due to the inclination of the can axis 27.

In the embodiment of Figs. 1, 2 and 3, the can axes always assume parallel positions, while in the embodiment of Fig. 4, the inclination of the individual axes is constantly

changing. It will be obvious that the desirable objects of this invention may be attained with any of the standard cooking and cooling machines now in commercial use, by merely tilting the machine bodily to cause the cans 16 therein to assume the tilted positions during treatment. The invention is not confined to heat treatment of the packed substance, but is equally applicable for effecting treatment by cooling. The effectiveness of the heat transfer may be varied by changing the degree of inclination of the can axes, and the results produced by but a slight inclination have been exceedingly meritorious, although a substantial inclination is probably more desirable as the rate of heat transfer is thereby enhanced.

It should be understood that it is not desired to limit the invention to the exact steps of the process herein specifically disclosed, for various modifications within the scope of the appended claims may occur to persons skilled in the art.

It is claimed and desired to secure by Letters Patent:—

1. The method of sterilizing food, which comprises, sealing batches of the food in containers, subjecting the sealed food to dry heat, and rotating the food laden containers about their longitudinal axes while maintaining these axes inclined at a constant angle relatively to a horizontal plane throughout the entire heating operation.

2. The method of sterilizing food, which comprises, sealing batches of the food in containers, advancing the food laden containers endwise through a zone of dry heat, and rotating the containers about their longitudinal axes while maintaining these axes inclined at a constant angle relatively to a horizontal plane throughout the entire heating operation.

3. The method of sterilizing food, which comprises, hermetically sealing batches of the food in cylindrical metallic containers, gradually advancing the food laden containers endwise through a zone of uniform dry heat, and rotating the containers about their longitudinal axes while maintaining these axes inclined in the direction of advancement and at a constant angle relatively to a horizontal plane throughout the entire heating operation.

In testimony whereof, the signature of the inventor is affixed hereto.

OSWALD H. HANSEN.
